CLAIM

The ornamental design for a trampoline enclosure support, as shown and described.

DESCRIPTION

FIG. 1 is a front elevational view of a trampoline enclosure support;

FIG. 2 is a left side elevational view of the trampoline enclosure support of FIG. 1;

FIG. 3 is a top view of the trampoline enclosure support of FIG. 1;

FIG. 4 is a rear elevational view of the trampoline enclosure support of FIG. 1;

FIG. 5 is a right side elevational view of the trampoline enclosure support of FIG. 1;

FIG. 6 is a perspective view of the trampoline enclosure support of FIG. 1;

FIG. 7 is a bottom view of the trampoline enclosure support of FIG. 1; and,

FIG. 8 is a perspective view of a plurality of trampoline enclosure supports disposed for use with a trampoline, enclosure, and base.

The broken lines shown in the FIGS. are for illustrative purposes only and form no part of the claimed design.

1 Claim, 8 Drawing Sheets
